FUR COAT CONSTRUCTION

Moses J. Schifrin, New York, N.Y.

Application July 17, 1946, Serial No. 684,195

1 Claim. (CL 24-65)

1 This invention relates to the manufacture of fur garments, more particularly to the making of fur coats from relatively large skins.

In recent years there has become available, as the result of inventions in fur processing, a fur known in the trade as "mouton." It is the skin of the sheep, clipped, dyed and having the fur fibers straightened in part so as to have a smooth appearance similar to seal or sheared beaver, rather than the wooly appearance of natural sheep skin. Such processed fur may be made, for example, as taught in U. S. Patent 2,225,267.

One of the beauties and at the same time one of the disadvantages of "mouton" is that the skins are relatively large and present unbroken areas of smooth glossy fur of even fiber length. To break up these areas by seams in a garment, except at those points where seams are normally expected to occur, as at the junction of the sleeves with the body, greatly detracts from the appearance of a garment and has been found to result in lowered consumer acceptance. Such a problem does not arise with fur garments made from the skins of smaller animals than sheep since buyers are accustomed to and expect garments made from numerous skins sewed together.

The average run of "mouton" pelts falls in a range having a usable length of between 32 and 36 inches. Only a very small percentage of pelts, about 7%, will be as long as 40 inches. By reason of this fact and because of the difficulty of selling garments in which visible seams occur in the length of the body, the trade has felt obliged to make up "mouton," for the most part, in what are currently known as jackets and short coats. Yet there exists a demand and a potentially large market for coats classified as "long." There is a difference of but a few inches between the "short" coat and the "long" coat, as classified in the trade, and indeed it has been possible to make a few long coats in the smaller sizes from the exceptional pelts among the available supply which are as long as 40 inches in usable fur.

The object of the present invention is to make possible the manufacture of coats in the "long" category from the regular run of mouton pelts under conditions which enhance rather than detract from the appearance of the garment and foster rather than interfere with consumer acceptance.

In speaking of "consumer acceptance" it should be realized that while the difference of a few inches in the length of a woman's coat or the presence or absence of a seam in the coat body may seem trifling to and pass the notice of the

average man unenlightened in the considerations of style and refinements of fabricating technique which hold sway in the women's garment industry, these are nevertheless factors of controlling industrial importance. The provision of the novel structures hereinafter described make a practical advance in the art of making fur coats of "mouton," and similar large smooth pelts, which potentially enlarge the production not only of the garments but of the processing of the skins and hence promote the progress of these useful arts. The production of acceptable "long" coats not only adds an item to the "mouton" garment line but it is an item which utilizes more fur.

As illustrative of the present invention, the present preferred embodiment thereof will now be described, in conjunction with the drawings in which:

20 Fig. 1 shows a pattern for some of the parts of a coat back, in the "long" coat class, laid out on a "mouton" skin, shown in dotted lines, illustrating how the uppermost and lowermost parts of the back are cut from a single pelt of ordinary length.

Fig. 2 shows a preferred shape of an insert, to be cut from another pelt, also forming a part of the back of the coat.

30 Fig. 3 shows, diagrammatically, the three parts of the back in assembled relation;

Figs. 4, 5 and 6 correspond, respectively, to Figs. 1, 2 and 3 but show the parts cut for and assembled into a front section, it being understood that a completed coat will comprise two such front sections secured, along one of their longitudinal edges, to the edges of the back section.

A fur coat in accordance with the invention has a body exclusive of sleeves, collars and the like, comprising three main sections, a back section and two front sections. A completed back section is shown in Fig. 3 and a completed front section in Fig. 6, it being understood that there will be two such front sections, for the right and left sides, which are the same except that one is the reverse of the other.

Each of said main sections comprises an upper part and a lower part cut from a single pelt of "mouton" or the like and utilizing the full usable length of the pelt. These upper and lower parts are later assembled in the same relationship in which they are cut out of the pelt so that the nap of the fur fibres lays in the same direction and hence reflects the light in the same way. Being cut from the same pelt, they will also have the identical color.

Referring to Fig. 1, the upper part B_1 and the lower part B_3 of a back section are shown laid out on a pelt P , shown in dotted lines. The pelt is first cut along the solid line outlines of the parts B_1 and B_3 and the marginal portions of the pelt outside of these lines are discarded. It will be noted, as is usual in coat construction, that the longitudinal edges 10 and 11 of the upper part B_1 and the corresponding edges 12 and 13 of the lower part B_3 are flared so that the bottom of the back section of the coat is wider than the top section to give the coat the proper drape. The single piece of fur thus cut out of the pelt P is next cut into the two parts B_1 and B_3 along the broken line 14. A small strip of fur lying between the broken line 14 and the broken line 15 is then trimmed off of part B_3 and discarded. It will be observed that the lower part B_3 is somewhat wider, between its edges 12 and 13, than is the upper part B_1 between the points 16 and 17, the upper corners of the lower part B_3 occurring at the points 18 and 19 and the sides 12 and 13 having the same slope as the sides 10 and 11, respectively.

Referring to Fig. 2, a separate piece of fur is cut from another pelt to form the insert B_2 , the upper edge 14' of which corresponds exactly to the cutting line 14 in Fig. 1. The lower edge of the insert B_2 corresponds in part to the cutting line 14 and in its central portion to the cutting line 15 as shown at 15'. The ends of this part have the same slope between the points 16'-18' and 17'-19' as the sides 10 and 11.

The parts B_1 , B_2 and B_3 are then sewed together in the manner shown in Fig. 3 to form a complete back section. Comparison of Figs. 1 and 3 shows how the back section has been lengthened by the vertical distance between the upper and lower edges of the insert B_2 . The fur from which the insert B_2 is made may be dyed a slightly different color than the parts B_1 and B_3 so as to contrast and at the same time blend therewith, the final effect being that a pleasing design is created around the lower portion of the coat body. This design has the appearance of being superimposed upon a single skin, since the parts B_1 and B_3 are from the same pelt. The objection which exists to lengthening a coat by the addition at the bottom of fur from a different pelt is eliminated and although seams are present between the parts of the back, they exist only in connection with a design thereon and are acceptable to consumers. By reason of the particular configuration of the insert B_2 and its angular relation to the bottom edge of the garment, the coat furthermore has the appearance of being lengthened by an amount in excess of the apparent width of the insert. The zig-zag strip produced by the insert B_2 actually has a width w , measured at right angles to any of its edges, which is its apparent width, but the amount by which the coat body is lengthened is greater as indicated at x and measured in the direction of the length of the coat body. The result is, in effect, an optical illusion, the coat being lengthened by an amount greater than the apparent width of the insert B_2 .

Referring to Figs. 4-6, the front sections of the coat are made in a similar manner, it being

understood that the top of the sections may be cut in any desired manner. Each front section is made of the three parts F_1 , F_2 and F_3 . Assuming that one is looking at the fur side of the parts in the drawings, the edge 20 of the part F_1 will be joined to the edge 10 of the part B_1 , the points 16" and 18" will be joined with the points 16' and 18', and the edges 22 and 12 will be joined together. The only difference between the cutting of the parts F_1 and F_3 and the parts B_1 and B_3 is that a further small segment indicated at 24 between the broken lines is cut out. It will be understood that the portion to the left of the dot-and-dash lines in Figs. 4 and 6 is folded over to make the facing of one of the front edges of the coat.

While only one embodiment of the invention has been specifically described, it is to be understood that various modifications may be made therein such as the precise shape of the inserts B_2 and F_2 and the corresponding shapes of the cutting lines 14 and 15 in the back section and corresponding lines in the front section. It is also contemplated that more than one insert may be used at more than one point in the coat body provided that the main body portions, including the uppermost and lowermost parts, are cut from a single pelt or pelts of the same characteristics so as not to destroy the appearance of continuity in the coat body as a whole. The invention is therefore to be construed broadly within the purview of the claim.

What is claimed is:

A fur coat body of "mouton" having a back section and two front sections joined to opposite edges of the back section; each of said sections consisting of an upper part forming the major area of the section, having an undulating lower edge, and cut from a single skin; a lower part forming a minor area of the section, having an undulating upper edge, and also cut from the single skin from which said upper part is cut; said upper and lower parts in each section being separated by an insert having an area no greater than the area of said lower part and shaped to correspond to the space between said upper and lower parts and sewed to the opposed edges thereof, the insert in each section being cut from a single skin of "mouton," the ends of the insert on the back section registering with the adjacent ends of the inserts in the front sections to form a continuous stripe around said body.

MOSES J. SCHIFRIN.
